DEEP WELL PUMPING APPARATUS

Abraham M. Herbsman and Neil B. Currier,
Huntington Park, and Rodney B. Campbell,
Walnut Park, Calif.; said Currier and said
Campbell assignors to said Herbsman

Application July 10, 1933, Serial No. 679,682

14 Claims. (Cl. 103—46)

Our invention relates to the deep well pumping art and is particularly useful in the pumping of deep oil wells.

In pumping deep oil wells, which frequently run down to depths of seventy-five hundred feet, there is a considerable problem introduced by the occurrence of gas at the lower end of the well which tends to interfere with the proper operation of the valves of the pump.

10 It is accordingly an important object of our invention to provide a deep well pumping apparatus, the operation of which will not be interfered with by the presence of a gas at the lower end of the well.

15 It is a further object of our invention to provide an efficient deep well pumping apparatus which is fluid operated.

Much of the crude petroleum produced forms an emulsion with water in the well while the oil is being pumped.

20 It is yet another object of our invention to provide a novel method of and apparatus for treating the oil as it is being pumped to substantially prevent the formation of this emulsion and 25 to break down any such emulsion as does form.

The manner of accomplishing the foregoing objects, as well as further objects and advantages, will be made manifest in the following description taken in connection with the accompanying drawings, in which:

Fig. 1 is a diagrammatic cross-sectional view of well illustrating an installation of a preferred embodiment of the apparatus of our invention.

Fig. 2 is a vertical sectional view of the motor of our apparatus.

Fig. 3 is an enlarged vertical sectional view of the gas pump of our apparatus.

Fig. 4 is an enlarged vertical sectional view of the upper half of the motor of our apparatus.

40 Fig. 5 is a view similar to Fig. 4 illustrating the parts of said motor positioned as just before the striking of a hammer blow on the valves of the motor.

45 Fig. 6 is a view similar to Fig. 5 illustrating the position of the parts just after such a hammer blow has been struck.

Fig. 7 is an enlarged vertical sectional view taken on the line 7—7 of Fig. 2 illustrating the valve detent mechanism of our invention.

50 Fig. 8 is a cross-sectional view taken on the line 8—8 of Fig. 4.

Fig. 9 is a cross-sectional view taken on the line 9—9 of Fig. 8.

55 Figs. 10, 11, 12, 13, and 14 are cross-sectional

views taken on correspondingly numbered lines in Fig. 4.

Referring specifically to the drawings, and particularly to Fig. 1, the preferred embodiment of the apparatus of our invention here shown includes a well casing 20 which is installed in a deep well 21 and is provided with a casing head 22 at its upper end. The casing 21 is provided with perforations 23 to permit a flow of well liquid into this casing. The upper end of the 10 casing 20 is connected to a pipe 25 which leads to a pump 26, this pump being adapted to draw liquid through a pipe 27 from a tank 28. Extending downwardly through the casing head 22 is a tube 29, the upper end of which connects with 15 the tank 28. Leading from the tank 28 to a suitable storage tank (not shown) is an overflow pipe 30.

Connecting with the pipe 25 is the discharge pipe 31 of a treating chemical pump 32, the 20 purpose of which will be made clear hereinafter.

In the normal installation of the apparatus of our invention the tubing 29 is the pump tubing of the well and the casing 20 is the final inside casing installed in the well. Connected to the 25 lower end of the pump tubing 29 is the motor and pump assembly 35 of our invention. This assembly includes a motor 36, a packer 37, a gas pump 38, and a liquid pump 39.

The motor 36 is practically completely shown 30 in Fig. 2 and includes upper and lower halves which are substantial duplicates of each other so that a description of the upper half of the motor will suffice for describing the entire motor. For distinguishing between upper and lower 35 halves of the motor, however, parts of the lower half will be identified by the same numbers as corresponding parts of the upper half with a prime attached. The motor 36 has upper and lower cylinders 42 and 42', adjacent ends of 40 these cylinders having collars 43 and 43', these collars being threadedly connected by a valve mechanism shell 44, this shell having openings 45 for the admission of fluid thereto. Disposed within the shell 44 and compressed between the 45 collars 43 and 43' is a valve cage 46, a spacer 47, and a valve cage 46'.

As before stated, the motor 36 includes upper and lower halves which are duplicates of each other. A line C—L drawn across the middle of 50 Fig. 2 indicates the dividing plane between these two halves. A description will now follow of the parts of the motor 36 above this line which, as before mentioned, will suffice for the entire motor unit.

The upper motor cylinder 42 shown in Fig. 1 and Fig. 4 is connected to the lower end of the pump tube 29. As shown in Fig. 4, a cup plunger 50 is slidably disposed in the cylinder 42 and is connected to the upper end of a piston sleeve 51 which extends downwardly through the motor 36 as shown in the drawings. The sleeve 51 is provided with holes 52 substantially at its middle and has a cam ring 53 and a stop ring 54 secured as by a pin to the exterior thereof as clearly shown in Fig. 4. Resting against the stop ring 54 is a valve hammer collar 55 which, as shown in Fig. 11, has two dogs 56 pivotally mounted at opposite sides thereof and is provided with passageways 57 through which liquid may pass by this collar. The dogs 56 are normally held in outward position by a circular band spring 58 as shown in Fig. 14. Yieldably holding the collar 55 against the stop ring 54 is a coil spring 59. Gripped between the cylinders 42 and the assembly collar 43 is a ring 60.

Slidably disposed about the piston sleeve 51 is a valve tappet ring 62, this ring having a number of passageways 63 formed therein for the purpose of allowing the free flow of fluid past this ring.

The valve cage 46, as shown in Figs. 4, 8, 9, and 12, has a packing gland 65 which makes a fluid-tight fit with the sleeve 51. Also four inlet passages 66 are formed through the cage 46, these ports having seats 67. The passages 66 are fluted to and from seats 67 as shown in Fig. 12, that is, both above and below these seats. Interspersed between the passages 66 are four passages 70, as shown in Fig. 9, these passages communicating through ports 71 with an annular space 72 between the sleeve 51 and the spacer tube 47. The passages 70 have valve seats 73, the portions of these passages disposed upwardly from these valve seats being fluted.

Fixed upon the spacer 47 is a valve lock housing 76 having a series of four passageways 77 formed therein and a series of detents 78 which are disposed opposite each of these passageways, the passageways 77 being in alignment with the passages 66 in the valve cage 46.

Referring now to Figs. 4 and 7, it is to be noted that chain-like valve assemblies 80 extend through each of the passages 66, 77, 77' and 66', these passages being in alignment in the motor 36. Each of the assemblies 80 includes a valve head 81 having a stem 82 and connected by a ball and socket joint 83 to a detent bar 84 having a detent recess 85. Each valve assembly 80 also has a valve head 86 provided with a stem 87 and connected by a screw adjustment link 88 to a detent bar 89 having a detent notch 90. The bars 84 and 89 are held in spaced relation by a spacer rod 91.

The valve assemblies 80 are connected at their upper ends by spider rings 93 and at their lower ends by spider rings 93', the stems 82 and 87 extending through these rings respectively and carrying anvil caps 94 and 94'.

Yieldably mounted on the spider ring 93, as shown in Fig. 9, are four exhaust valves 96 which are aligned with and extend into upper ends of the passages 70 in the valve cage 46. Owing to the fact that the passages 70 above the valve seats 73 are fluted laterally, the valves 96 are open when raised from these seats as shown in Fig. 9.

An opposite pair of the valve assemblies 80 is assembled as shown in Fig. 7, while the alternate pair is reversed so that the valves 86 are disposed

opposite the valve seats 67 and the valves 81 are disposed adjacent the valve seats 67'.

The lower motor cylinder 42' connects to the packer 37 and the latter supports the gas pump 38 as shown in Fig. 3. The gas pump 38 includes a head 100 which screws upon a nipple 101 extending downwardly from the packer 37. The head 100 has a packing gland 102 which makes a fluid-tight fit with the piston sleeve 51. Mounted in the head 100 are spring pressed intake valves 103 which receive gas from the space outside the head 100 and admit this inwardly into the space about the piston sleeve 51. Screwed onto the head 100 is a gas pump cylinder 105, the lower end of which is screwed onto a head 106 which is a duplicate of the head 100. Slidably disposed within the cylinder 105 is a gas pump plunger 112 which divides the interior of this cylinder into pump chambers 113 and 114. The sleeve 51 is parted, threaded, and screwed into opposite ends of the plunger 112 as clearly shown in Fig. 3. Pump exhaust valves 115 are provided in the plunger 112, these valves receiving gas from upper and lower pump chambers 113 and 114 and discharging this gas through ports 116 into the interior of the sleeve 51.

The lower end of the piston sleeve 51 extends downwardly through the packing gland of the gas pump head 106 into the upper end of a liquid pump barrel 120 of the liquid pump 39. As shown in Fig. 1, this liquid pump has a plunger 121 having upper and lower working valves 122 and 123, and the cylinder 120 has a standing valve 124 provided at its lower end. The lower end of the motor piston sleeve 51 connects to the upper end of the plunger 121 so that reciprocation of this sleeve causes operation of the pump 39.

Provided on the upper end of the motor piston 50 is a check valve 130, which allows a flow of liquid upwardly through the piston 50 but prevents a downward flow therethrough.

Operation

In order to operate the apparatus 35 after it is installed as above described the engine or other means for operating the pump 26 is set in motion so as to draw well liquid from the tank 28 and force this downward between the tube 29 and the casing 20. This liquid enters the ports 45 shown in Figs. 2 and 4. The views in Figs. 2 and 4 illustrate the parts of the motor 36 while the piston unit thereof (including pistons 50 and 50' and sleeve 51) is travelling downward. As will be noted, the valve heads 81 are seated on the valve seats 67 so as to shut off access of the fluid entering the ports 45 to the upper cylinder 42. As shown in Fig. 7, however, the valves 86 are open at this time, thus permitting the fluid entering the ports 45 to pass downwardly into the lower cylinder 42', this fluid operating against the lower piston 50' and causing downward movement of the pistons and the connecting piston sleeve 51.

The valve assemblies 80 are at this time held in their uppermost positions by contact of the detents 78 with the notches 90, as shown in Fig. 7. This holds up the spider rings 93 and 93' and holds open the exhaust valves 96, permitting liquid in the cylinder 42 to be discharged therefrom through the ports 71 and the holes 52 into the interior of the sleeve 51. The spider 93', however, holds the valves 96' (not shown) closed so as to confine the fluid discharged into the lower cylinder 42' and thus make the force of this fluid effective in causing a downward power stroke.

As the piston and sleeve unit of the motor 36

moves downwardly the dogs 56 are brought into contact with the ring 60 as shown in Fig. 5 so as to halt the downward movement of the valve hammer collar 55. Further downward movement of the sleeve 51, however, brings the cam ring 53 into contact with the dogs 56 so as to swing these inwardly out of contact with the ring 60. This is not accomplished, however, before a considerable pressure is placed on the collar 55 by the spring 59 so that when the release of the dogs on the ring 60 takes place the collar 55 is shot downwardly with considerable force to strike a hammer blow upon the valve tappet rings 62 which transmits the blow to the anvil caps 94, this blow suddenly driving the valve assemblies 80 downward, thus opening the valves 81, closing the valve 86, closing the valves 96, and opening the valves 96'. The valve assemblies 80 are held in their new positions by the detents 78 dropping into the notches 85 in the same manner as the detents 78' are shown in the notches 90 in Fig. 7. The shift in the positions of the valve assemblies 80 results in shutting off the fluid from the lower motor cylinder 42', opening the exhaust valves 96' leading from that cylinder, closing the exhaust valves 90 leading from the upper cylinder, and opening the valves 81 admitting power fluid to the upper cylinder.

When the piston and sleeve unit of the motor 36 reaches its upwardmost position the valve assemblies 80 are shifted upwardly by a hammer blow from beneath in exactly the same manner as they were shifted downwardly in the operation above described.

In this manner the piston and sleeve unit is continually reciprocated by the fluid which enters the ports 45. This reciprocation effects a pumping action of the gas pump 38, any gas in the casing 20 just beneath the packer 37 being drawn through the valves 103 of the heads 100 and 106, compressed in the chambers 113 and 114, and, passing through the valves 115, is discharged inwardly through the ports 116 into the interior of the sleeve 51. Also, reciprocation of the sleeve 51 operates the plunger 121 of the liquid pump 39 so as to draw a stream of liquid from the lower end of the casing 20 and force this upwardly through the piston sleeve 51 into the lower end of the pump tubing 29.

As a result of operating the apparatus 35 of our invention in the manner above described well liquid is drawn from the bottom of the well 21 and forced upwardly through the pump tubing 29 into the tank 28 from which a portion of this liquid is withdrawn by the pump 26 and forced downwardly between the tubing 29 and casing 20 for the operation of the motor 36. An excess of well fluid equal to the amount discharged upwardly by the pump 39 flows outwardly from the tank 28 through the overflow pipe 30.

While we have shown and described the invention as operating through the medium of well liquid, it is to be understood that the motor 36 might also be actuated by the use of a gas such as the gas obtained from the well itself, where this is an oil well, this gas being forced downwardly and actuating the motor 36 in the same manner as where liquid is employed for this purpose.

The check valve 131 is provided to permit a resetting of the valve assemblies 80 in their lower extreme positions in case these assemblies should become stalled in a middle position. This resetting is effected by reversing the flow of fluid in the apparatus 35 by shutting off valve 131 in the line 30 and reversing the pump 26 to force

liquid down through the tube 29. This urges the piston 50 into its lowermost position which, as above described, hammers the valve assemblies into their full lower positions. The valve 131 is then opened and normal operation of the apparatus 35 resumed.

Where the apparatus 35 is used in pumping a deep oil well, the formation of emulsion between the oil and water in the well may be substantially prevented by the injection of a suitable treating chemical from the pump 32 into the operating liquid pipe 25. This chemical is thoroughly mixed with the operating liquid which transfers the chemical to the pumped oil when both are discharged into the motor piston sleeve 51 as above described.

The presence of this chemical thoroughly diffused throughout the oil while it is at the bottom of the well under tremendous pressure greatly decreases the formation of emulsion which would otherwise occur as the oil rises to the surface and this pressure is removed from the oil. Furthermore, this same chemical operates to break down whatever emulsion there is in the oil while the latter lies in storage.

If there should be an appreciable quantity of emulsion in the oil when it reaches the surface, the oil should preferably be heated, according to the usual practice in chemically treating oil for the breaking of emulsions, before the oil is placed in storage.

Chemicals which are preferred for use in the treating method of our invention are those disclosed in copending applications for United States Letters Patent of Abraham M. Herbsman Serial 35 No. 536,490, filed May 11, 1931; Serial No. 545,153, filed June 17, 1931; and Serial No. 568,211, filed October 10, 1931.

While only a single preferred embodiment of the apparatus of our invention has been shown and described, it is to be understood that numerous changes may be made in this without departing from the spirit of the invention or the scope of the appended claims.

We claim as our invention:

1. In a deep well pumping apparatus the combination of: a well casing; a tube extending downward into said casing; a packer between said casing and said tube near the level from which it is desired to pump liquid from said well, said tube dividing the space in said casing into two separate passageways between said level and the top of said casing, one of said passageways being inside said tube and the other being between said tube and casing; pump means for pumping liquid from said well below said packing and discharging it into one of said passageways; and a separate pump means for compressing gas accumulating in said well below said packer and discharging it into the same passageway that said liquid is discharged into.

2. A combination as in claim 1 in which a fluid motor is provided on the lower end of said tubing, said motor being connected to both of said pumps; and means for delivering fluid under pressure down the other of said passageways to operate said motor.

3. In a deep well pumping apparatus the combination of: a well casing; a tube extending downward into said casing; a packer between said casing and said tube near the level from which it is desired to pump liquid from said well; pump means for pumping liquid from said well below said packing and discharging it into said tube;

separate pump means for compressing gas accumulating in said well below said packer and discharging it into said tube; a fluid motor for driving both of said pumps, said motor being located at the lower end of said tubing; and means to deliver fluid under pressure downward between said tube and said casing to operate said motor.

4. A combination as in claim 1 in which a hydraulic motor is provided at the lower end of said tube for operating both of said pumps; and means for delivering downward through the other of said passageways for the purpose of operating said motor a liquid of substantially the same characteristic as that being pumped from said well, the exhaust from said motor being discharged into the first of said passageways with the liquid being pumped.

5. A combination as in claim 3 in which said motor is hydraulically operated and the fluid delivered thereto is substantially of the same characteristics as the liquid being pumped so as to counterbalance the gravity head of said liquid.

6. In a deep well pumping apparatus the combination of: a well casing; a tube extending downward into said casing; a motor housing connected to the bottom of said tube; a motor cylinder formed within said housing; a piston operating within said cylinder; a piston sleeve connected to said piston and operating reciprocably in said cylinder; a pump cylinder connected to the lower end of said housing; a pump plunger operating in said pump cylinder; valve means on said pump for controlling the pumping of liquid thereby, said plunger being connected to the lower end of said piston sleeve so that a closed passage is formed between said plunger and the interior of said sleeve; a packer between said motor housing and said casing; valve means in said motor housing receiving fluid from the space between said housing and said casing and delivering it to said motor cylinder and discharging the exhaust from said cylinder into said piston sleeve; and means for delivering fluid under pressure downward through the space between said tube and said casing to operate said motor to cause liquid to be pumped by said pump upwardly through said piston sleeve into said tubing.

7. A combination as in claim 6 in which a gas pump cylinder is concentrically disposed about said sleeve and forms a connecting link between said motor cylinder and said liquid pump cylinder; a gas piston fixed on said piston sleeve and operating in said gas cylinder; and valve means for said gas pump cylinder and gas piston which connect to the space in said well beneath said packer and to the interior of said sleeve so that, upon the operation of said motor, gas is drawn from said well beneath said packer, compressed, and expelled into said sleeve.

8. In a deep well pumping apparatus the combination of: a well casing; a tube extending downward into said casing; a pair of motor cylinders, the upper of which connects to the lower end of said tube; a valve housing connecting said motor cylinders; valve mechanism provided in said housing, there being a central opening in said valve housing provided with a suitable packing; pistons having longitudinal central openings and disposed in said motor cylinders; a piston sleeve extending through said valve housing and connecting said pistons; reciprocating pump means connecting to the lower end of the lower of said cylinders; a plunger in said pump means connected to the lower end of said sleeve; a packer in said casing below said valve housing;

and means for delivering fluid downwardly between said tube and said casing to said valve mechanism to operate said motor pistons in said cylinders to reciprocate said plunger and thereby pump liquid from beneath said packer upwardly in said tube.

9. In a deep well pumping apparatus the combination of: a well casing; a tube extending downward into said casing, said tube dividing the space in said casing into a plurality of separate vertical 10 passageways; a pair of motor cylinders, the upper of which connects to the lower end of said tube; a valve housing connecting said motor cylinders; valve means provided in said valve housing, there being a central opening in said valve housing 15 provided with a suitable packing; pistons having longitudinal central openings and disposed in said motor cylinders; a piston sleeve extending through said valve housing and connecting said pistons; reciprocating pump means connecting to the 20 lower end of the lower of said cylinders; a plunger in said pump means connected to the lower end of said sleeve; a packer in said casing below said valve housing; and means for delivering fluid under pressure down one of said passageways to 25 operate said motor piston to reciprocate said plunger and pump liquid from beneath said packer upward into the other of said passageways.

10. In a fluid motor the combination of: a cylinder; a piston; valve means; and hammer 30 means operated by said piston to travel at a greater speed than that of said piston for delivering a sudden hammer-like blow on said valve means for changing the position of the latter when said piston is closed to one end of a given 35 stroke in said cylinder.

11. In combination: a pair of cylinders; valve means disposed between said cylinders; pistons in said cylinders; a piston connecting member connecting said pistons and extending through said 40 valve means to form a reciprocating piston unit; hammer means for delivering a blow upon said valve means as said piston unit approaches an extreme position; and means actuated and controlled by said unit for operating said hammer 45 means at a speed in excess of that of said unit.

12. A combination as in claim 11 in which a plurality of hammer means as aforesaid are provided, said plurality of hammer means delivering blows to said valve means as said piston unit 50 approaches each of two opposite extreme positions.

13. In a deep well pumping apparatus the combination of: a well casing; a tube extending downward into said casing; a valve housing formed 55 by a given section of said tube; motor cylinders formed by sections of said tube at opposite ends of said valve housing, there being openings in the wall of said valve housing to admit operating fluid into said housing from the space between 60 said casing and said tube; valve supporting head means in said housing; packing gland means in said head means; a piston sleeve slidable in said gland means; pistons provided on opposite ends of said sleeve and disposed in said cylinders, there 65 being an exhaust port in the wall of said sleeve where this sleeve is disposed within said valve head; valve means in said head; means responsive to reciprocation of said pistons for actuating said valves to admit operating fluid from said 70 openings into said cylinders and to admit exhaust fluid from said cylinders through said port and into said piston sleeve and thereby cause said pistons to reciprocate; means associated with said pistons, piston sleeve, and tube to form a pump 75

for pumping liquid upwardly through said tube when said pistons reciprocate; a packer between said tube and said casing below said openings; and means for delivering operating fluid downwardly between said tube and casing to cause said pistons to reciprocate.

14. A combination as in claim 13 in which said valve supporting head means includes two spaced heads having central apertures supplied with 10 packing glands, and a cylindrical shell connecting said apertures, said piston sleeve extending

through said glands and said shell, each of said heads also having exhaust passages delivering exhaust fluid into the space between said sleeve and said shell, said fluid passing from said space through the aforesaid port in said sleeve into the interior thereof and thence upwardly into the aforesaid tube. 5
